MEANS FOR COMPENSATING FOR IRREGULARITIES IN MANUFACTURING ARTIFICIAL SILK THREAD

Louis E. Lovett, Cleveland Heights, Ohio, assignor to Industrial Rayon Corporation, Cleveland, Ohio, a corporation of Delaware

Application May 20, 1938, Serial No. 209,049

4 Claims. (Cl. 18—8)

This invention relates to means for compensating for irregularities in the manufacture of thread or the like, particularly artificial silk thread. The practice contemplated by the invention involves imparting to the thread or the like a varying amount of stretch, preferably as or just after the thread or the like is formed. Among other things, it is the purpose of the invention to make it possible to exert upon the thread or the like an inversely varying stretch complementing any tension developed in the package in which the thread or the like is collected, this in order that the final product may have characteristics as nearly uniform as possible.

If, as is often the case, a varying tension is developed in a given length of thread or the like as or after it is gathered in or on the collecting means, a predetermined amount of stretch sufficient to compensate therefor may by means of the present invention be introduced into the thread or the like as the package is being built up. This may be accomplished, for instance, by imparting little or no tension to the thread or the like contained in the first layer to be wound in the package, but modifying the tension as necessary in succeeding layers. Thus if the inner layers are subsequently stretched under tension, as happens, for example, in the drying of thread which is wound while wet, the finished product can be made to have a degree of stretch which is uniform throughout the entire length of thread or the like.

It is well known in the art of manufacturing multiple filament viscose artificial silk thread by the spool-spinning process that the thread first wound upon the spool; i. e., the thread on the inside of the package, is subjected in drying to a degree of tension quite different from that induced in the turns of thread going to make up the outer portion of the package. According to the present invention, this difference is compensated for by introducing between the thread forming means and the collecting device a flared thread-advancing thread store device, preferably of cantilever form, adapted to move axially as the package of thread on the spool grows larger so as to shift the path of the thread toward the large end of the device. In the illustrated embodiment of the invention, representing one of a variety of different types of apparatus, the invention is shown as thus employed in the manufacture of multiple filament viscose artificial silk thread.

In the accompanying drawings, in which like reference characters refer to like parts through-

5 out, Figure 1 represents an elevation with parts in section of a conventional spool-spinning machine embodying the principles of the present invention. Figure 2 is a front elevation of the machine from line 2—2 of Figure 1. Figure 3 is an end view of a typical form of flared thread-advancing thread store device which may be employed to advantage in the apparatus of the invention. Figure 4 is a section with parts in elevation of the thread-advancing thread store device as seen from line 4—4 of Figure 3.

In the embodiment of the invention illustrated in Figures 1 and 2, the threads 6 are formed by the extrusion of viscose into the coagulating bath 10 contained in the trough 11 extending longitudinally of the machine. Such threads are formed by means of a series of thread forming units disposed therealong each of which comprises a spinning pump 7, a mass tube 8 and a spinneret 9. Each of the pumps 7 is supplied with viscose from the supply conduit 12 and is actuated by the drive shaft 13. Both the supply conduit 12 and the drive shaft 13 extend along the entire length of the machine, which is two-sided after the manner of spool-spinning machines of the kind heretofore known.

15 The thread 6 is directed in each case from the spin bath 10 through the manually adjustable stationary guide 14 to a retractable thread-advancing thread store device 15 disposed above and at an angle to the axis of the longitudinally extending trough 11. The thread-advancing store device 15 is not only supported from one end thereof but is adapted to advance the thread 6 in a series of closely spaced generally helical turns from the supported to the unsupported end thereof. After having been advanced over the surface of said thread store device 15, thread 6 is delivered to a manually adjustable stationary guide 16 from 20 which it proceeds to the rotating spin spool 17. It is wound on the spin spool 17 in the usual way by means of the reciprocating guide 18 supported and actuated by the traverse arm 19.

25 One form of thread-advancing thread store device which is adapted to advantageous use in the practice of the instant invention is shown in detail in Figures 3 and 4. It operates on rotation in a manner generally similar to that of the reel shown, described and claimed in copending application Serial No. 652,089 for "Winding reel," filed January 16, 1933, by Walter F. Knebusch, (Patent 2,210,914). The device shown in the accompanying drawings differs from the reel therein disclosed principally in that it is of cantilever form and flared adjacent the unsupported end thereof.

The reel comprises two rigid cage members 21 and 22 made up of a plurality of longitudinally extending bar members 23 and 24 alternately disposed with respect to each other. Reel member 21, which is referred to as the concentric member, embodies a cylindrical central portion 25 which supports and imparts the necessary rigidity to the bar members 23. Said reel member 21 is mounted concentrically upon the drive shaft 26 and is held against a shoulder on said shaft by the cap nut 27. In the illustrated embodiment, the concentric member 21 is caused to rotate with the drive shaft 26 by means of a pin 28 passing through the shaft and extending into the slot 29 formed in the hub of said member 21.

The second reel member 22, known as the eccentric member, is shown as being cage-like in form and made up of the bars 24 which are provided at their outer ends with an internal reinforcing ring 31 and at their inner ends with an external reinforcing rib 32 by means of which the cage-like reel member 22 is mounted concentrically upon the annular supporting member 33. The annular supporting member 33 is rotatably mounted upon shank 34 with its axis in spaced and inclined relationship to the axis of concentric member 21. Drive shaft 26 may be journalled as illustrated in shank 34.

As a result of the above-described construction, when the drive shaft 26 is rotated the cage member 21 which is mounted concentrically upon said shaft likewise rotates and, because of the interdigitating relation of the bars 23 and 24, drives the rotatably mounted cage member 22 by bar-to-bar contact. Radial displacement of the bars of one cage member with respect to those of the other cage member causes the thread to be carried first by one set of bars and then by the other. The inclined relationship between the sets causes the thread to advance longitudinally of the reel. On rotation of the reel, both factors taken together result in progression of the thread from one end of the reel to the other in the form of an advancing helix made up of a large number of closely spaced, generally helical turns.

Due to the configuration of the retractable reel illustrated in the accompanying drawings, the desired amount of tension is imparted to the thread as it traverses a path upon said reel defined by stationary lead-on guide 14 and stationary take-off guide 16. During the period of time required to build up the package of thread on the spin spool 17, the reel 15 as a whole is gradually retracted toward the center of the apparatus; i. e., away from the operating face of the machine. Due to the fixed position of guides 14 and 16, this retractive movement in effect causes the path followed by thread 6 to be moved toward the discharge end of the reel 15; i. e., toward the portion of maximum diameter. The result is to increase the diameters of some or all of the turns going to make up the helix into which the thread is formed.

The periphery of reel 15 is shown as being regularly flared from an initial cylindrical lead-on portion adjacent the supported end of the reel, practically to the unsupported end thereof, where the cross-sectional diameter of the reel is at its maximum. In a reel of given length, the included angle of the flared portion of the reel 70 fixes the maximum amount of stretch that can be exerted upon the thread, the degree of stretch increasing as the thread path is caused to approach the unsupported end of the reel. By thus progressively increasing the diameters of the 75

path traversed by the thread 6 on the flared portion of the reel, a correspondingly increasing stretch is imparted to the thread, the introduction of such stretch coinciding approximately with the formation of the portion of the thread package on which only a minimum degree of tension is developed by the drying operation. The provision of an initial lead-on portion of cylindrical shape renders it possible to minimize variations in denier of the kind which would occur if the reel were continuously flared from one end to the other.

Retraction of the reel may be accomplished by a rack 37 secured to a shank 34 on reel 15 and 15 a cooperating segmental gear 38 actuated by a longitudinally extending shaft 39 preferably rotated at a very slow speed by means of a motor (not shown). Shank 34 is slidably mounted in a bracket 41 secured to frame member 42 extending lengthwise of the machine as a whole. Shank 34 is prevented from turning by the key 43 held in bracket 41 which slides in a slot cut lengthwise of said shank 34 as well as by the rack 37 which slides in a slot cut in the inside of the bracket 41. Shaft 39, which serves to operate a series of segmental gears 38 actuating a corresponding number of reels 15, may be supported by bearing brackets mounted on frame member 42.

In order to insure positive rotation of the reel 15 while it is being retracted, it is necessary to provide for endwise movement of the drive shaft 26 of the reel. This may be accomplished by means of helical gears 44 and 45, gear 45 being fixed to a drive shaft 46 extending longitudinally of the machine and operating a plurality of similar reels. Gear 44 may be provided with pin 47 which cooperates with a groove cut lengthwise of the shaft 26 to permit the shaft to slide axially. A stationary bracket 48 secured to longitudinally extending frame member 49 prevents the gear 44 from moving laterally on the shaft 26 as the reel is retracted. A key 51 (Figure 4) or other suitable means cooperates with the circular keyway 52 in preventing endwise movement of the shaft 26 with respect to shank 34.

It is desirable that a reversing transmission (not shown) be located at the driving end of shaft 39 in order that, upon the completion of the operation of forming the thread package on the spool 17, the reel 15 may be returned to the starting position for replacement of the filled spool by an empty spool.

In conventional spool-spinning practice, the thread is wound upon the spool directly after being withdrawn from the spin bath, in consequence of which fact that thread comprising the first few layers, when subjected to drying, tends to shrink but is prevented from so doing by the spool. The tensile stress thereby introduced in the thread is gradually decreased in the succeeding layers lying at or near the center of the package, this because the thread in this portion of the package is permitted to shrink against the resilient cushion formed by the innermost layers. The outermost layers of the package, being the first to dry, tend to shrink against the intermediate layers while they are still wet and are thereby prevented from shrinking as freely as might be desired.

As stated, one of the purposes of the invention is to impart to the thread as it is being wound on the spool an amount of stretch sufficient to equalize the tension developed in the intermediate and outermost thread layers by the drying operation. It has been pointed out that this can

be done by employing a regularly flared reel of the kind disclosed in Figures 3 and 4 in which an initial cylindrical lead-on portion is followed by a frusto-conical portion flared toward the unsupported end of the reel. If a greater degree of precision is necessary, it is possible to employ a reel having a tapered portion at the unsupported end thereof by means of which the amount of tension imparted to the thread in traversing this portion of the reel may be decreased to any desired extent.

Thus it may be desirable to increase the tension in the thread from the minimum when the thread package is started upon the spin spool to a maximum when a certain portion of the package is wound, say 10,000 to 12,000 meters of thread, in which portion of the package the thread when dried experiences the least amount of shrinkage, and thereafter to decrease the tension until the completed package, approximately 16,000 meters, is formed. To accomplish this, the reel may be constructed with a flared portion extending from the cylindrical lead-on portion to a predetermined maximum diameter, such flared portion being followed by a reversely tapered portion extending thence to the unsupported end of the reel. Thus after reaching the portion of maximum diameter, the thread may be advanced therebeyond to the tapered portion of the reel, where the tension imparted to the thread is relaxed as desired.

Thread which has been subjected in the course of its manufacture to non-uniform stresses will not possess the high degree of uniformity which the trade demands. If non-uniform tensile stresses are imposed upon the thread in the course of its production, the dyeing of the fabric made therefrom will produce "shiners"; i. e., bright streaks which result from a modified affinity of the thread for the dyestuff, in addition to which the cloth made from such thread will not hold its shape satisfactorily because of the fact that different portions of the fabric are formed from thread having a non-uniform capacity for elongation. By the present invention, thread which possesses uniform properties throughout its length can be readily obtained.

With only slight modifications in the method and means herein disclosed, such, for example, as the substitution of a double-ended reel for the cantilever reel illustrated, the invention may be adapted to any of the known processes for the production of artificial silk thread. Although the illustrated embodiment of the invention is described as applied to the viscose process, it should be understood that the invention is equally adaptable to the cuprammonium, cellulose acetate and nitrocellulose processes, as well as to the manufacture of thread or the like of still other kinds. It is intended that the patent shall cover, by suitable expression in the appended claims, whatever features of patentable novelty reside in the invention.

What is claimed is:

1. Apparatus for the manufacture of artificial silk thread having uniform dyeing properties comprising a thread supply source; means for

collecting the thread in package form upon a spool; disposed between said thread supply source and said spool, a unitary thread-advancing thread store device upon which the thread is advanced in an axial direction in the form of a helix made up of a plurality of closely spaced turns, said thread store device having a periphery including a cylindrical portion to which the thread passes from said supply source and a contiguous frusto-conical portion flared in the direction of advance of the thread; means defining the path of travel of the thread upon the periphery of said thread store device; and means for moving said thread store device relatively to said defining means, whereby the helix formed by the thread is moved in an axial direction along the periphery of the device.

2. Apparatus for the manufacture of artificial silk thread having uniform dyeing characteristics comprising a thread supply source; means for collecting the thread in package form upon a spool; disposed between said thread supply source and said spool, a unitary thread-advancing thread store device which is supported from one end only upon which the thread is advanced in the direction of the unsupported end thereof in the form of a helix made up of a plurality of closely spaced turns, said thread store device having a periphery including a cylindrical portion to which the thread passes from said supply source and a contiguous frusto-conical portion flared toward said unsupported end; means defining the path of travel of the thread upon the periphery of said thread store device; and means for moving said thread store device relatively to said defining means, whereby the helix formed by the thread is moved in an axial direction along the periphery of the device.

3. Apparatus for the production of thread of synthetic origin possessing uniform dyeing characteristics comprising a thread supply source; a unitary thread-advancing reel of cantilever construction the periphery of which is made up of a cylindrical portion to which the thread passes from said supply source and a contiguous frusto-conical portion flared toward the unsupported end thereof; means for supporting said reel; means for moving said reel with respect to its supporting means whereby the path of travel of said thread is moved in an axial direction along the periphery of the device; and means for collecting the thread in package form upon a spool.

4. Apparatus for the manufacture of artificial silk thread of uniform dyeing characteristics comprising a thread supply source; a unitary thread-advancing thread store device the periphery of which is made up of a cylindrical portion to which the thread passes from said supply source and a contiguous frusto-conical portion flared in the direction of advance of the thread; means defining the path of travel of the thread upon the thread store device; means for moving said thread store device in an axial direction with respect to said defining means; and means for collecting the thread in package form upon a spool.

LOUIS E. LOVETT.
